UNITED STATES PATENT OFFICE

2,606,397

MAGNETIC TOY MOUSE

Vincent James Marchese, Brooklyn, N. Y.

Application June 17, 1946, Serial No. 677,299

5 Claims. (Cl. 46—45)

1

This invention relates to improvements in toys.

The primary object of this invention is the provision of an improved toy construction comprising a base structure wherein is located an electromagnet with means to energize it at will and the representation of some animated object associated upon the base having an armature adapted to be attracted by the electromagnet; the armature being so associated upon the animated object that energizing of the electromagnet for attraction of the armature will cause the animated object to perform motions of various sorts which may be mystifying, entertaining, amusing and educational.

Other objects and advantages of the invention will be apparent from the following detailed description, taken in connection with the accompanying drawings, forming a part of this specification, and in which drawings:

Figure 1 is a perspective view showing the improved toy arrangement consisting of a base and some representation of an animate subject.

Figure 2 is a plan view of the subject which in this case is in bug or insect form showing certain structural features; the view being a bottom view.

Figure 3 is a longitudinal cross sectional view taken through the subject.

Figure 4 is a plan view of the base structure with the top covering removed and more particularly showing the electromagnet and diagrammatically showing its hookup in a circuit.

Figure 5 is a transverse cross sectional view taken through the base structure substantially on the line 5—5 of Figure 4.

Figure 6 is a transverse cross sectional view taken through the base structure showing the electromagnet energized in its circuit for attracting the armature in the bug or subject and showing the bug in some animated posture.

Figure 7 is a transverse cross sectional view taken through the bug or subject substantially on the line 7—7 of Figure 2.

In the drawings, wherein for the purpose of illustration is shown only a preferred embodiment of the invention, the letter A may generally designate a toy which may consist of a base structure B having an electromagnet C embedded therein and connected with a source of power such as a battery D. The representation of some animate subject E is provided with an armature F therein and in form to be attracted by the electromagnet upon energizing of the latter in order to cause unique and natural movements of the subject.

2

The base B may take various forms. Preferably it is rather thin and formed of some light weight material such as balsa wood, papier mâché, plastic, aluminum or the like. In the form shown it is polygonal in outline and the dimensions, of course, may vary. It is provided with a depression 10 centrally therein adapted to receive the electromagnet structure C. The latter consists of an iron or other type core 11 having pole portions 12. It is recessed on the top, bottom and side surfaces thereof to receive insulated copper wire 20. Of course the winding may be insulated with respect to the core and the pole surfaces may lie flush with the top surface of the base body. The winding of the electromagnet terminates in end portions 22 and 23 which are socketed within suitable grooves 24 provided inwardly of the top surface of the base. Since the electromagnet structure will be furnished as a unit, suitable flexible leads 26 may be spliced to the ends 22 and 23 as shown at 27. The leads 26 may be connected operatively to a source of power, or battery D and an operating switch 30 may be placed in the circuit. Of course the battery and the wiring may be hidden at some convenient location remote from observers and the leads extend from one edge of the base as shown; the grooves 24 being filled with some sealing compound 35, as shown more particularly in Figure 6. The entire base is covered with a very thin gauge covering 31, which may be of fabric or paper and, of course, it entirely secretes and hides the electromagnet and its wiring extensions.

Referring to the object E which may simulate some form of animation, such as an insect, bird, bee, fish or even a human being, the same comprises a body portion 40 which may be made of some soft material such as balsa wood, plastic or metal. The shape of the body may vary but in the drawings the same is rather of oval-shape formation having rounded bottom surfacing 41. At the front the body 40 may be provided with a recess 43 wherein is hidden a spiral spring 44 which extends from the recess 43 and supports the head 45 so that as an incident of movement of the body the head will nod. Suitable antenna 47 may be placed upon the head.

The body 40 is forwardly supported by front legs 50 and a second pair of legs 51 rearwardly of the front legs 50. These legs may be of springy wire and their ends are embedded in the body 40 in any approved manner. They support the body 40 in normal manner and to avoid injury to the top surface of the base or its covering the

wire legs 50 and 51 are tipped at 53 with some protecting material which will admit of the ready sliding of the bug over the top surface of the base or its covering. The round bottom surfacing 41 intermediate the ends of the body 40 rests upon the base surface, which is designated by the dot and dash line 55 in Figure 3 of the drawings.

Rear leg structure for the object is important, in that it should not offer any appreciable resistance to rising movement of the insect or object. To that end I provide in the lower portion of the body slightly to the center of the body a hollow tube 60 which extends entirely through the body and is open at its ends. A rather U-shaped leg arrangement designated broadly at 61 is provided. It includes divergently disposed legs 62 and 63 and a connecting bight portion 64 which extends through the hollow tube 60 and is freely rotatable therein. The bug or object is partially supported by its body intermediate its ends, as shown in Figure 3, and this enables the legs 62 and 63 to rest with a life-like appearance upon the surface 55 of the base, without offering any support for the object itself.

The armature F is of steel, magnetic alloy or other desired material and it is socketed in a recess 70 disposed at the rear end of the body 50 in the under surface thereof entirely rearwardly of the leg mounting tube 60. The armature F may take the form shown in Figure 2, that is, the form of a trapezoid, its wider end being forwardly, and in cross section the armature 70 is arcuate with its exposed surface conforming to the curvature of the body 40 and preferably lying flush therewith. The armature may be suitably coated to entirely hide the same to the eye of an observer and in any event it is not readily seen because of its location in the body.

Upon closing the switch 30 of the circuit it is readily obvious that the electromagnet will attract the armature and cause the object to perform antics or movements, such as to assume the position shown in Figure 6.

I do not wish to be limited to any particular form and shape of body nor to any particular type of decoration located thereon. The eyes, mouth and nose of the object may be arranged to express such traits as fear, belligerency, affection, stupidity or the like, and any type of color design or other embellishment may be provided.

It is within the contemplation of this invention to locate more than one armature in any object provided and to locate the same in such relation that for educational purposes the electromagnet when energized will cause the object to move with natural movements. However, for entertaining purposes the electromagnet is usually placed so that upon energizing the electromagnet the armature will be attracted for causing the object to move with unique and unnatural movements. The closing of the circuit with the arrangement shown will enable the bug to stand up and even turn completely over on its back. Of course the degree to which the movements are caused can be controlled by the strength of the magnet. It is quite obvious that the leg arrangement will always cooperate perfectly in relation to its placement with the armature.

Various changes in the shape, size and arrangement of parts may be made to the form of invention herein shown and described without departing from the spirit of the invention or the scope of the following claims.

I claim:

1. In a toy device the combination of a base having a toy article supporting surface, an electromagnet carried by said base in non-obstructing relation with respect to said supporting surface, an article simulating some object freely movable upon the supporting surface of the base having a convexly rounded bottom surface engaging the base supporting surface and in contact therewith so that the article can have a rocking action upon said base, an eccentrically disposed armature mounted upon said article in position to be spaced above the supporting surface of the base when the object is at normal gravity rest upon the base with the electromagnet inactive so that upon attraction of the armature by the electromagnet the article will be caused to rock and move upon said base, and means to selectively energize and de-energize said electromagnet.
2. In a toy device the combination of a base having a top article supporting surface, an electromagnet carried by said base in non-obstructing relation with respect to said supporting surface, an article in the form of some object freely movable upon the supporting surface having a convexly rounded bottom surface engaging the base supporting surface and in contact therewith so that the article can have a rocking action upon said base, an eccentrically disposed armature mounted upon said article in position to be spaced above the supporting surface of the base when the article is resting normally by gravity upon the base with the electromagnet inactive, so that upon attraction of the armature by the electromagnet the article will be caused to rock and move upon said base, means to selectively energize and de-energize said electromagnet, and yieldable spring type leg means connected with said article for supporting it at a portion thereof spaced from said supporting surface of the base.
3. As an article of manufacture a toy in the form of some animated object comprising a body portion, a head, spring means marginally connecting the head to the body portion and permitting the head to nod with respect to the body portion, said body portion having a convexly rounded undersurface to permit the same to have a rocking action upon some supporting surface, spring type yieldable supporting legs connected to the body portion adjacent to the head and yieldably supporting said body portion adjacent to the head above the supporting surface, and an armature mounted upon the body portion directly opposite the head and in position to be spaced above the supporting surface upon which the body portion is resting when in a normal gravity resting position.
4. As an article of manufacture a toy object in the form of some animated object comprising a body portion, a head, a spring means connecting the head marginally to the body portion and permitting the head to nod with respect to the body portion, said body portion having a convexly rounded undersurface to permit the same to have a rolling action upon some supporting surface, spring type yieldable supporting legs connected to the body portion adjacent to the head and yieldably supporting said body portion adjacent to the head above the supporting surface, an armature mounted upon the body portion directly opposite the head and in position to be spaced above a surface upon which the body portion is resting in a normal gravity position upon the supporting surface, and freely pivoted leg

means mounted upon the body portion adjacent to said armature offering no resistance to support of the body portion upon said supporting surface.

5. In a toy device the combination of a supporting base having a top flat supporting surface, a current controlled electromagnet carried by the base in non-obstructing relation with respect to said flat supporting surface, means to selectively energize and de-energize said electromagnet, an object in animate form including an elongated body portion having a convexly rounded undersurface resting upon said supporting surface of the base, front spring type yieldable legs connected with said body portion and supporting the front portion of said body above the supporting surface of the base, a head, spring means connecting the head to the front of the body portion so that the head will nod upon movement of the body, an armature eccentrically mounted upon the body at the rear thereof normally spaced above the supporting surface of the base during normal gravity rest of the body portion upon said base, so that upon energizing of the electromag-

net the armature upon attraction will cause the body to rock and move upon said base, and rear leg means connected to said body offering no resistance to support of the body upon said base.

VINCENT JAMES MARCHESE.
